UNITED STATES PATENT OFFICE.

CHARLES H. SEIFERT, OF BARBERTON, OHIO, ASSIGNOR TO THE BABCOCK & WILCOX COMPANY, OF BAYONNE, NEW JERSEY, A CORPORATION OF NEW JERSEY.

CASING.

Application filed April 13, 1927. Serial No. 183,434.

My present invention relates to casings which are particularly useful in conjunction with heat insulating material for enclosing furnaces, boilers and the like, to prevent the passage of heat from such structures, although it will be understood that my invention is not limited to this use.

My invention will best be understood by reference to the following description and the annexed drawings, in which I have illustrated one embodiment of my invention, and in which Fig. 1 is a fragmentary front view of a casing embodying my invention; Fig. 2 is a sectional view taken along the plane of the line 2—2 of Fig. 1; Fig. 3 is a fragmentary front view similar to Fig. 1 and illustrating a small portion of Fig. 1 on an enlarged scale; Fig. 4 is a section taken along the plane of the line 4—4 of Fig. 3, and Fig. 5 is a section taken along the plane of the line 5—5 of Fig. 3.

Like reference characters indicate like parts throughout the drawings.

For heat-insulating casings, in which, as indicated, my invention is particularly useful, there is commonly provided a layer of heat-insulating material which is ordinarily covered on the exterior by a sheet metal covering. These coverings are made up of metallic plates, and ordinarily the casing is further provided with stiffening members extending along the sheet metal covering to hold the parts in position, the ends of these stiffening members being ordinarily connected to the framing of the furnace or other structure to which the casing is applied. The casing covering and the stiffening members, as heretofore usually constructed, have been arranged so that there are large metallic paths for heat flow through the layer of heat-insulating material, thus nullifying to a large degree the effect of heat insulation. By my present invention, I provide a simple means for holding the parts of the casing in position which at the same time minimizes or entirely avoids any such metallic paths through the heat-insulating layer.

In the illustrated embodiment of my invention, a refractory wall 10 is covered with a layer of heat-insulating material indicated generally at 11, and here shown as comprising two separate layers 111 and 112, and the heat-insulating layer is covered by a wall or casing comprising panel plates 12 which are unflanged, and of substantially uniform

thickness throughout, and are preferably rectangular in form, so that they can readily be cut from sheet metal into panels of desired dimensions. The panels are preferably spaced sufficiently to permit the passage of bolts through the joints therebetween as will be hereinafter more specifically described.

On the inner side of the panels 12 are located members extending in different directions, indicated generally at 13 (Fig. 3), which, when the wall or casing is vertical, preferably extend horizontally and vertically. The channel irons 131, which extend in one direction and which may be the horizontal channels when the casing is vertically arranged, are preferably continuous, while the vertical channel irons 132 are discontinuous and are fitted between the channel irons 131 and preferably secured thereto as by welding, as illustrated at 14 (see Figs. 3 and 4). The channel irons 13 overlap the joints formed between the panels 12, and the open sides thereof preferably extend away from the panel plates as illustrated in Figs. 4 and 5, the channels preferably being filled with a hardened plastic material as indicated at 15.

The ends of the channels 13 are preferably secured suitably (in a manner not illustrated) to the framework at the sides of the furnace or other structure, so that the channels 13 constitute a rigid frame which is self-supporting and which is capable of supporting the heat-insulating casing when the same is used in connection therewith.

Members, indicated generally at 16 and which are also illustrated as channel irons 161 and 162, are also provided on the opposite side of the panel plates and which overlap the joints between the panel plates, the channel irons on the outside of the casing preferably running parallel and directly over the channel irons on the inside of the panel plates. The channel irons on the outside, however, are preferably deeper than those on the inside, and the vertical channels may be of greater depth than the horizontal channels as best shown in Figs. 4 and 5. The one set of the outer channels, as 161, may also be continuous while the other set of channels 162 are discontinuous. The outer continuous channels 161 extend at an angle to the inner continuous channels 131. The discontinuous outer channels 162 fit closely in between the continuous channels, but it is usually unnecessary that they should be secured

together as is the case with the inner channels. The outer channels 161 and 162 preferably open towards the panel plates, so that the flanges thereof engage the panel plates 5 on opposite sides of joints between the panels as illustrated in Figs. 4 and 5. The outer channels and the inner channels are secured together as by bolts 17 which pass between adjacent panel plates 12 and which serve to 10 clamp the two sets of channels against the opposite sides of the panel plates, suitable layers of packing material 18 preferably being interposed between the edges of the panel plates 12 and the channel irons 13 as best 15 shown in Figs. 4 and 5.

In the embodiment of my invention illustrated, where the wall or casing is used in conjunction with a body or layer of heat-insulating material, such body is preferably made up of two layers, the one comprising blocks 111 which may be formed of material commonly known as fire backing, and which are preferably of the same depth as the channel irons 13, so that the edges of the 25 channel irons and the inner face of the blocks 111 lie in the same or substantially the same plane. The body of heat-insulating material 11 also comprises an inner layer 112 which may be formed of blocks of fire 30 backing which are fitted together, and the joints of which may overlap with the joints between the blocks 111.

It will be evident that my invention provides a wall or a casing comprising a plurality of separate panel plates which are of substantially uniform thickness and which may readily be formed and assembled in position and that these plates are held in position by a simple yet rugged structure, and 40 without the necessity of providing holes in the panel plates for bolts, thereby correspondingly simplifying the construction. The construction also provides for the replacement of an individual panel, without 45 disturbing the position of those adjacent.

It will also be evident that no metallic paths are provided through the layer of heat-insulating material, in conjunction with which I have illustrated my invention, 50 which makes my invention particularly useful for this purpose.

It will be understood that the arrangement which I have described is merely illustrative and that the embodiment of my invention 55 may be modified. It will also be understood that the wall or casing comprising the panel plates 12 and the structure by which these plates are secured in position may be used independently of the heat-insulating layer.

60 I claim:—

1. A casing comprising a plurality of rectangular panel plates, channel members located on opposite sides of said panel plates and overlapping the joints therebetween, 65 channel members on each side of said plates

extending in different directions and means for securing said channel members together and clamping them against opposite sides of said panel plates.

2. A casing comprising a plurality of rectangular panel plates, channel members extending in different directions located at one side of said panel plates and overlapping the joints therebetween, the channel members extending in one direction being continuous and those extending in the other direction being discontinuous and fitted between and secured to said continuous members, thereby forming a framework, and second members located on the opposite side of said panel plates and overlapping the joints therebetween and extending in different directions and means passing between said panel plates for securing said second members and said channel members together and clamping them against opposite sides of said panel plates.

3. A casing comprising a plurality of rectangular panel plates, members located on opposite sides of said panel plates and overlapping the joints therebetween, the members on at least one side of said panel plates comprising continuous members extending in one direction and discontinuous members extending in another direction fitted between and secured to said continuous members to form a frame, and means for clamping said members against opposite sides of said panel plates.

4. A heat insulating casing comprising a plurality of separate panel plates, members located on opposite sides of said plates and overlapping the joints therebetween, means for securing said members together, and a heat insulating layer on one side of 100 said panel plates, said layer comprising a portion fitted between the members on one side of said plate.

5. A heat-insulating casing comprising a plurality of separate panel plates, channel members located on opposite sides of said plates and overlapping the joints therebetween, means passing between said panel plates for securing said channel members together and clamping them against opposite faces of said panel plates, and a heat-insulating layer at one side of said panel plates, said layer comprising a portion fitted between the associated channel members.

6. A heat-insulating casing comprising a plurality of separate panel plates, channel members located on opposite sides of said panel plates and overlapping the joints therebetween, means for securing said channel members together and clamping them against opposite sides of said panel plates, the channel members on one side of said panel plates opening away from the plates and being filled with hardened plastic material, and a heat-insulating layer at one 130

side of said panel plates, said layer comprising a portion fitted between said members.

7. A heat-insulating casing comprising a plurality of separate panel plates, members located on opposite sides of said panel plates and overlapping the joints therebetween, heat-insulating packing material interposed between one set of said members and said panel plates, means for securing said members together and clamping them against the opposite sides of said panel plates, and a heat-insulating layer at one side of said panel plates.

15 8. A heat-insulating casing comprising a plurality of separate panel plates, channel members located on opposite sides of said plates and overlapping the joints therebetween, heat-insulating packing material interposed between the plates and the channel irons at one side thereof, means for securing said channel irons together and clamping them against opposite sides of said panel plates and a heat-insulating layer located at 25 one side of said panel plates.

9. In combination, a refractory wall and a covering therefor comprising a layer of heat insulating material over said refractory wall and a casing comprising a plurality of panel plates, members located on opposite sides of said panel plates and overlapping the joints therebetween, members

on each side of said plates extending in different directions, and means for securing said members together with the edges of 35 panel plates clamped between the two.

10. In combination, a refractory wall and a covering therefor comprising a layer of heat insulating material over said refractory wall and a casing comprising a plurality of panel plates, members located on opposite sides of said panel plates and overlapping the joints therebetween, members on each side of said plates extending in different directions, and means for securing 45 said members together with the edges of panel plates clamped between the two, the layer of heat insulating material filling the space between said members on one side of said plates.

50 11. In combination, a refractory wall and a covering therefor comprising a layer of heat insulating material over said refractory wall and a casing comprising a plurality of panel plates, channel members located 55 on opposite sides of said panel plates and overlapping the joints therebetween, the channel members on each side of said plates extending in different directions, and means for securing said members together with the 60 edges of panel plates clamped between the two.

CHARLES H. SEIFERT.
